UNITED STATES PATENT OFFICE.

LOYAL D. DOBBS, OF MINNEAPOLIS, MINNESOTA, ASSIGNOR TO MINNEAPOLIS BEDDING COMPANY, OF MINNEAPOLIS, MINNESOTA, A CORPORATION OF MINNESOTA.

FOLDING BED.

Application filed October 23, 1926. Serial No. 143,643.

This invention relates to improvements in folding beds of the type employing a bed frame pivoted adjacent one end to a base and adapted to swing from a normal inoperative upright position, to a substantially horizontal operative position, for use. The base upon which the bed frame is pivotally mounted, is adapted to be supported upon the floor, and provides a support for the bed frame, mattress and bedding, when the frame is folded or swung to its inoperative upright position, and, when the latter is lowered to its operative position, the base provides a support for the head end of the bed frame only, the foot end of the frame being supported upon suitable legs.

The supporting base of such a bed is usually made comparatively small to take up as little floor space as possible, when the bed is in folded upright position. The base, however, must be of sufficient size to prevent it from tilting or tipping forwardly, when the bed frame, including the mattress and bedding, is lowered to its operative position. This tendency toward tipping is caused by the center of gravity of the bed frame, mattress and bedding being swung outwardly from over the center of the base, when the bed is lowered, and as a result of the spring mechanism, usually provided for counterbalancing the weight of the bed frame, etc. To overcome this tipping tendency in beds of this type the base is provided with a board bearing on the floor usually obtained by extending one side of the base outwardly toward the foot-end of the bed. Such a base obviously takes up considerable room on the floor and is particularly noticeable when the bed frame is raised to an upright position and it is therefore desirable to provide a comparatively small or narrow base for a folding bed and at the same time eliminate any danger of the base tipping when the bed frame is lowered to a horizontal position. The object therefore of this invention is to provide means operable by movement of the pivotally mounted bed frame, to positively prevent the base from tipping or tilting, when the bed is being lowered to its operative position.

A further and more specific object is to provide such a bed including a base having an extension frame slidably connected there-

with at the foot end thereof and engaging the floor, and operatively connected to the bed frame whereby, when the bed frame is lowered to its operative position, the extension frame, supporting the foot end of the base, will automatically be moved in a direction toward the foot-end of the bed to increase the effective supporting length of the base to prevent it from tipping; and, when the bed frame is returned to its normal upright position, the extension frame will automatically be retracted or returned to its normal position.

A further object is to provide a folding bed including a base having a bed frame pivotally mounted thereon, the head end of the base being supported upon casters and the foot end thereof being supported upon similar casters mounted in an extension frame slidably mounted in runways provided in the lower portion of the base; and a simple link mechanism connecting the extension frame with the bed frame whereby, when the bed frame is in upright inoperative position, the extension frame will be retracted to render the base comparatively small in size, and when the bed is lowered to an operative position, the extension frame will be extended in a direction lengthwise of the bed frame, thereby increasing the effective supporting length or size of the base to the extent that the base cannot tilt forwardly when the bed frame and contents are lowered to an operative position.

Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown as various changes may be made within the scope of the claims which follow.

In the accompanying drawings, Figure 1 is a side elevational view showing a folding bed in folded position and with the invention embodied therein, the dotted lines indicating the positions of the bed frame and the extension frame, when the bed is in unfolded position;

Figure 2 is a vertical sectional view of the

base showing the runways in the lower portion thereof in which the extension frame is slidably mounted;

Figure 3 is a similar view showing the extension frame extended;

Figure 4 is a sectional plan view on the line 4—4 of Figure 2; and

Figure 5 is a detail sectional view on the line 5—5 of Figure 3.

10 The novel bed featured in this invention comprises a base 6 having its head end supported upon casters 7 as shown in Figure 1. A bed frame 8 is pivoted at one end to the base 6 and comprises the usual spring fabric 9 adapted to support the mattress and bedding 10, indicated in dotted lines in Figure 1. Legs 11 are pivotally connected to the foot end of the bed frame 8 by means of links 12 and 13. The pivotal connections of the 20 legs 11 with the bed frame 8 are such as to permit the legs to assume the folded position shown in Figure 1, when the bed frame is in an upright inoperative position, and when the frame is lowered to its operative position, shown in dotted lines, the legs 11 will be swung outwardly to a position at right angles to the bed frame to provide a support for the foot end of the frame.

25 Barrels 14 are provided upon the base 6 at each side thereof, and each barrel is provided with a forked lug 15 to which the bed frame 8 is pivotally mounted by pins 16, passing through the lugs 15 and apertures provided in castings 17, secured to the side rails of the bed frame. Plungers 18 are pivotally connected to each casting 17 and have their lower ends engaging compression springs 19 mounted in the barrels 14 as shown in Figure 1. These barrels, springs and plungers function to counterbalance the weight of the bed frame and bedding, when the bed frame is lowered to its operative position, shown in dotted lines in Figure 1. The details of construction and operation of the 40 above mentioned spring mechanism, is shown and described in detail in the prior pending application of John M. Thompson, Serial #67,852, filed Nov. 9, 1925.

45 The supporting base of a folding bed of this type is usually made comparatively small so as to take up as little floor space as possible, when the bed is in folded inoperative position. The base, however, must be of sufficient size to prevent it from tilting or tipping forwardly, when the bed frame, including the mattress and bedding, is lowered to its operative position. This tendency toward tipping is usually caused by the center of gravity of the bed frame, mattress and bedding being swung outwardly from over the center of the base when the bed is lowered, and further, as a result of the spring mechanism provided for counterbalancing the weight of the bed frame. To overcome this 55 tendency toward tipping, the casters at the

head end of the frame 6 and the casters or supporting members engaging the floor at the foot end of the base, must usually be spaced a considerable distance from one another. The means provided for thus preventing the bed from tipping consists of movably connecting the casters 21 with the supporting base 6. Referring to Figures 2 and 3, it will be noted that the casters 21 are mounted in an extension frame 22 slidably engaged with the base 6. Anti-friction rollers 23 are mounted at the head end of the extension frame 22 adapted to roll in runways 24 provided in the lower portion of the base 6. Similar anti-friction rollers 25 are mounted in forked arms 26 on the base 6 adapted to engage the extension frame 22, as particularly shown in Figure 3.

60 The means provided for moving the extension frame 22 from its retracted position shown in Figure 2, to its extended position shown in Figure 3, consists of a link mechanism pivotally connecting the frame 22 with the bed frame 8. This link mechanism includes a pair of links 27 pivotally connected at one end to the foot end of the extension frame 22. Link members 28 are similarly connected at one end to the base 6 and have their opposite ends pivotally connected with the links 27 intermediate the ends thereof, by means of pivot pins 29. Each link 27 is provided with an offset end portion 31 terminally pivotally connected with connecting bars 32 having pivotal connections with the bed frame 8 by means of pivots 33. The relative lengths of the links, link members and connecting bars, and their connections with the extension frame, base and bed frame, are such that when the bed frame 8 is in its folded upright position, the extension frame 22 in which the casters 21 are mounted, will be retracted or moved into the base 6 to the position shown in full lines in Figures 1 and 2. When the bed frame 8 is lowered to substantially a horizontal position, as indicated in 65 dotted lines in Figure 1 and full line in Figure 3, the link mechanism will operate to move the extension frame 22 outwardly from the base 6 in a direction toward the foot end of the bed, thereby increasing the distance 70 between the casters 7 and 21 to the extent that the base cannot tip or tilt forwardly when the bed frame is lowered to its operative position.

75 By the employment of this novel extension frame in connection with the supporting base 6, the size of the base, in direction lengthwise of the bed, will be reduced to a minimum when the bed is in its folded inoperative position. The movement of the casters 21 and the extension frame 22 is such that as the bed frame 8 is being lowered to its operative position, the casters 21 will simultaneously be moved in a direction toward the foot end of the bed, thereby positively preventing the 80

bed from tilting or tipping forwardly, as frequently occurs with beds of this type of ordinary construction, unless the supporting bases thereof are made larger than is desirable in furniture of this kind.

Its construction is comparatively simple and inexpensive and requires no attention on the part of the operator when swinging the bed from one position to another.

10 I claim as my invention:

1. A device of the class described including a base having its head end supported upon a floor, a bed frame pivoted adjacent one end to said base and normally held in an upright position and adapted to be swung to a substantially horizontal operative position, an extension frame having means by which it is slidably connected with said base for supporting the foot end thereof and adapted to be extended therefrom to increase the length of the base in a direction towards the foot end of the bed, a link pivotally connected at one end to said extension frame, a second link member pivotally connected at one end to the base and having its other end terminally pivotally connected with said first-mentioned link, and a third link pivotally connected with the first mentioned link and with the bed frame, to operate said first link as a lever, said links being arranged to move said extension frame to its extended position, when said bed frame is lowered, and to return the same to its retracted position when said bed frame is raised.

35 2. A device of the class described including a base having its head end supported upon a floor, a bed frame pivoted adjacent one end to said base, runways in the lower portion of the base arranged in a direction lengthwise of the bed, an extension frame slidably mounted in said runways and providing a support for the foot end of the base, casters on said extension frame engaging the floor, a link pivot-
40 ed at one end to said extension frame, a mem-
ber pivoted at one end to the base and having its other end pivotally connected with said link intermediate the ends thereof, and a connect-
45 ing bar pivoted at one end to said bed frame and having its other end terminally pivotally connected with said link at the free-
50 end thereof, and adapted to operate said link and member to move said extension frame to its extended position when said bed frame is lowered, and to return it to its normal retract-
55 ed position, when the bed frame is raised to an upright position.

3. A device of the class described including a base having its head end supported upon a floor, a bed frame pivoted adjacent one end to said base, runways in the lower portion of the base arranged in a direction lengthwise of the bed, an extension frame slidably mounted in said runways and providing a support for the foot end of the base, casters on said extension frame engaging the floor, links piv-

oted at one end to said extension frame, sec-
ond link members pivoted at one end to the base and having their other ends pivotally connected with said first mentioned links inter-
mediate the ends thereof, each of said first
70 mentioned links having an offset end, and connect-
ing bars pivoted at one end to said bed frame and having their other ends terminally pivotally connected with said offset ends and adapted to operate said links and members
75 to move said extension frame to its extended position when said bed frame is lowered, and to return it to its normal retracted position, when the bed frame is raised to an upright position.

80 4. A folding bed comprising a base, having an extension provided with means by which it is horizontally slidably thereon forwardly toward the foot end of the bed, a bed frame pivoted to the base, a link pivoted to the base, a second link pivoted to the slidable extension, said links pivoted together, said second link having an extension rearwardly of its pivotal connection with the first link, and a third link pivoted to said frame and to the extension of
90 the second link, and arranged to operate the second link as a lever to translate the slidable extension forwardly.

5. A folding bed comprising a base having an extension provided with means by which it is horizontally slidable thereon forwardly toward the foot end of the bed, a bed frame pivoted to the base, a link pivoted to the base, a second link pivoted to the slidable extension, said links pivoted together at a point inter-
95 mediate their pivotal connection with base and extension, said second link having an ex-
100 tension rearwardly of its pivotal connection with the first link, and a third link pivoted to said frame and to the extension of the sec-
105 ond link, and arranged to operate the second link as a lever to translate the slidable extension forwardly.

6. A folding bed comprising a base having an extension provided with means by which it is horizontally slidable upon the base for-
110 wardly toward the foot end of the bed, the bed frame pivoted to the base, a link pivoted to the base, a second link pivoted at one end to the slidable extension forwardly of the
115 pivotal connection of the first link, said second link being pivoted to said first link, and a third link pivoted to said frame and to said second link rearwardly of the link-connecting pivotal point.

7. A folding bed comprising a base having an extension provided with means by which it is horizontally slidable upon the base for-
120 wardly toward the foot end of the bed, the bed frame pivoted to the base, a link pivoted to the base, a second link pivoted at one end to the slidable extension forwardly of the
125 pivot of the first link, said second link being intermediately pivoted to said first link at a point intermediate the other pivots, and a
130

third link pivoted to said frame and to said second link rearwardly of the link-connecting pivotal point.

8. A folding bed comprising a base, having an extension provided with means by which it is slidable thereon, forwardly toward the foot end of the bed, a bed frame pivoted to said base, a link pivoted to the base, a second link pivoted to the slidable extension forwardly of the pivot of the first link, and fulcruming upon the first mentioned link, and a third link pivoted to said frame and to the second link at one side of the fulcrum point.

9. A folding bed comprising a base, having an extension provided with means by which it is horizontally slidable thereon forwardly toward the foot end of the bed, a bed frame pivoted to the base, a pair of links, respectively only connected to base and slidable extension, and pivotally connected together above the base, and a link pivoted only to the frame and to one of the links at a point at one side of the connecting pivot of the links, the arrangement being such that the last mentioned link acts on the link to which it is connected, to translate the slidable base extension in a forward direction as the bed frame is swung downwardly.

10. A folding bed comprising a base having an extension provided with means by which it is horizontally slidable thereon forwardly toward the foot end of the bed, a bed frame pivoted to the base, a pair of links, respectively only connected to base and slidable extension, and pivotally connected together above the base, and a link pivoted only to the frame and to one of the links at a point at

one side of the connecting pivot of the links, the arrangement being such that the last mentioned link acts to translate the slidable base extension in a forward direction as the bed frame is swung downwardly, the general direction of the movement of the last link being intermediate of the pivotal points of the pair of links.

11. A folding bed comprising a base having an extension provided with means by which it is horizontally slidable thereon toward the foot end of the bed, a bed frame pivoted to the base at a point thereabove, a link pivoted to the base, a lever having one arm pivoted to the slidable extension forwardly of the pivot of the first mentioned link, said link and lever pivoted together at a point above and intermediate of the first mentioned pivotal points, a third link pivoted to the frame and to that arm of said lever lying rearwardly of the connecting pivot for the link and lever, said last mentioned link lying above the first mentioned links and arranged to rock the lever about the link-connecting pivot, to advance the base extension as the frame is drawn downwardly, the initial thrust of the last link with respect to the levers being generally in a direction between the first mentioned pivotal points of the link and lever, the arrangement being such that when the extension reaches its forward limit of translation the last mentioned link assumes a substantially vertical position.

In witness whereof, I have hereunto set my hand this 20th day of October 1926.

LOYAL D. DOBBS.
